UNITED STATES PATENT OFFICE.

THOMAS E. JORDAN, OF MELDEN, MASSACHUSETTS, ASSIGNOR TO OLIVER WHYTE CO. INC., OF BOSTON, MASSACHUSETTS, A CORPORATION OF MASSACHUSETTS.

SEESAW.

1,422,766.

Specification of Letters Patent. Patented July 11, 1922.

Application filed June 12, 1920. Serial No. 388,619.

To all whom it may concern:

Be it known that I, THOMAS E. JORDAN, a citizen of the United States, residing at Mel-
den, county of Middlesex, State of Massa-
chusetts, have invented an Improvement in
5 Seesaws, of which the following description,
in connection with the accompanying draw-
ing, is a specification, like characters on the
drawing representing like parts.

10 This invention relates to see-saws and has
for its object to provide an improved see-
saw having the novel features hereinafter
set forth.

15 In order to give an understanding of my
invention, I have illustrated in the drawings
a selected embodiment thereof which will
now be described, after which the novel fea-
tures will be pointed out in the appended
claims.

20 Fig. 1 is a side view of a see-saw embody-
ing my invention;

Fig. 2 is an enlarged sectional view on the
line 2—2, Fig. 1;

Fig. 3 is a view on the line 3—3, Fig. 2.

25 Fig. 4 is a section on the line 4—4, Fig. 2.

My improved see-saw comprises a stand or
support 1 on which is pivotally mounted a
beam 2 having seats 3 at the ends thereof.
The stand 1 is pyramidal in shape, and it
30 comprises four angle-iron legs 4 which are
inclined to each other and to the floor, and
all of which are fastened at their upper ends
to a head-piece 5. The legs 4 are connected
at their lower ends by the cross-pieces 6.

35 The head 5 is cap-shaped, is rectangular in
cross-section, and has the four sides 26 ar-
ranged with the opposite sides inclined rela-
tive to each other and with adjacent sides at
right angles to each other. The upper ends
40 of the angle-iron legs 4 are set within the
cap 5 with the angles resting against the
sides thereof, and said legs are secured to the
cap by any suitable means, such as bolts,
screws, or rivets 7. The cap-piece 5 carries

45 a fulcrum member 8 on which the beam 2
fulcrums. This fulcrum member has the ful-
crum edge 9 and the two sides or arms 10
that embrace the sides of the beam 2. It is
also provided with the cylindrical stem 11
50 which fits an opening in the top of the cap 5.
This fulcrum member can, therefore, turn in
the cap 5, thus giving a swivel connection be-
tween the beam and the stand.

The beam is of novel construction, it being
55 made relatively narrow so that the persons

using the device can occupy the seats 3 with
comfort, and it also being made so as to give
it all the required strength. I propose to
make the beam of channel iron with the
channel directed downwardly, as shown in 60
Fig. 2, and then to fill the channel iron with
a strip 12 of wood. The channel iron gives
the necessary strength to the beam, so that
it will support the weight on the end with-
out bending and by filling the channel iron 65
with a wooden strip 12, any tendency of the
channel iron to twist or warp is obviated.
The under edge of the channel iron is pro-
vided with a plurality of notches 13 to re-
ceive the fulcrum edge 9. One of the notches 70
is placed at the center of the beam and others
at one side of the center, so that by properly
shifting the beam relative to the fulcrum
member, the arms of the beam may be given
the proper relative length so that persons of 75
different weights will be evenly balanced.

I will preferably provide a pair of han-
dles at each end of the beam to be grasped
by the occupant of each seat 3. The handles
are indicated at 14 and they are secured to 80
a U-shaped bracket 15 which in turn is se-
cured to the beam. The bracket is provided
with the portion 16 that embraces the beam
and is fastened in place by the screw or
bolt 17. 85

I claim:

1. A see-saw comprising a pyramidal
standard having a four-sided cap member
arranged with adjacent sides at right angles
to each other and each side inclined outward-
ly and downwardly, and angle-iron legs hav-
ing their upper ends inserted within the cap
member at the corners thereof so that each
flange of each leg bears flatly against one
side of the cap member, means securing said 95
legs to said cap member, and a channel-iron
beam member fulcrumed on said cap member
and provided at its ends with seats. 90

2. A see-saw comprising a pyramidal
standard having a four-sided cap member ar-
ranged with adjacent sides at right angles to
each other and each side inclined outwardly
and downwardly, and angle-iron legs having
their upper ends inserted within the cap
member and secured to the sides thereof, and
a channel-iron beam member fulcrumed on
said cap member and arranged with the
channel directed downwardly, said channel
being filled with a strip of wood, and seats
at the end of the beam member. 105

3. In a see-saw, the combination with a stand, of a fulcrum member having a shank or stem swiveled in the stand and provided with a fulcrum edge, and two arms extending upwardly at each end thereof, and a channel-iron beam member received between said arms and fulcrumed on said fulcrum edge.

4. A see-saw comprising a pyramidal 10 standard having a four-sided cap member arranged with adjacent sides at right angles to each other and each side inclined outwardly and downwardly, and angle-iron legs

having their upper ends inserted within the cap member at the corners thereof so that 15 each flange of each leg bears flatly against one side of the cap member, means securing said legs to said cap member, and a channel-iron beam member fulcrumed on said cap member and provided at its ends with seats, 20 said channel iron being filled from one end to the other with a strip of wood.

In testimony whereof, I have signed my name to this specification.

THOMAS E. JORDAN.
